(57) **CLAIM**

The ornamental design for a firearm wall mount, as shown and described.

DESCRIPTION

FIG. 1 is a perspective view of a firearm wall mount showing my new design;

FIG. 2 is a perspective view the firearm wall mount of FIG. 1, shown in an alternate use state;

FIG. 3 is a rear view of the firearm wall mount of FIG. 1;

FIG. 4 is a front view thereof;

FIG. 5 is a left view thereof;

FIG. 6 is a right view thereof;

FIG. 7 is a top view thereof; and,

FIG. 8 is a bottom view thereof.

The broken lines in the drawings are included for the purpose of illustrating portions of the firearm wall mount and form no part of the claimed design.
